(57) CLAIM

The ornamental design for a multi-bladed thicket knife, as shown and described.

DESCRIPTION

FIG. 1 is a perspective view of a multi-bladed thicket knife showing one embodiment of our new design;

FIG. 2 is a top view thereof, with the bottom view being identical thereto;

FIG. 3 is a view of one of the three identical curved sides; and,

FIG. 4 is a view directed onto one of the three identical corners.
